UNITED STATES PATENT OFFICE

JAMES R. COE, OF WATERBURY, CONNECTICUT, ASSIGNOR TO THE AMERICAN BRASS COMPANY, OF WATERBURY, CONNECTICUT, A CORPORATION OF CONNECTICUT

METAL CARRIER

Application filed December 23, 1929. Serial No. 415,917.

This invention relates to a metal carrier such as is used for transporting flat metal bars, tubes, rods and the like about a mill, as for example from rolling or drawing machines to annealing furnaces or any other place where it is desired to carry these elements. This carrier is particularly adapted for use in pairs for carrying metal bars, tubes, rods and the like from rolling or drawing machines to the annealing furnaces where they are lowered by crane onto sheet steel pans which are pulled into and through the annealing furnaces, the pans, carriers and metal being equally subjected to the heat in the furnace. After leaving the furnace the hot metal bars, tubes, rods and the like, with the carriers are lifted from the pan by crane and immersed in the cooling tank and then returned to the rolling or drawing machine. It is, therefore, an object of this invention to provide an improved construction of carrier which will have the requisite strength and rigidity so that they will not crush or deform under heavy loads when hot. It is also an object of the invention to provide a carrier which is of sufficient width to stand alone and facilitate loading at the machine, and of such weight that they may be easily positioned by hand. It is another object of the invention to provide an improved construction of carrier which will have great strength and stiffness in proportion to the amount of metal in and, therefore, the weight of the carrier. With the foregoing and other objects in view, the invention consists in certain novel features of construction, combinations and arrangements of parts as will be more fully disclosed in connection with the accompanying drawing.

In this drawing

Fig. 1 is a side elevation of a carrier involving my improved construction showing how it is used for carrying metal tubes, bars or the like.

Fig. 2 is an end view thereof.

Fig. 3 is a top plan view showing the preferred method of making the carriers.

Fig. 4 shows a transverse section of a standard pipe which may be used for form-

ing the enclosing casing for the base portion of the carrier.

Fig. 5 is a cross section showing intermediate operations in the making of the carrier.

Fig. 6 is a transverse section of the base portion of a completed carrier. 55

Fig. 7 is a transverse section of a metal plate which may be used in place of the pipe as the enclosing casing, and

Fig. 8 is a transverse section of the base portion of a completed carrier applying the member of Fig. 7. 60

As indicated above, these carriers are intended to be used in pairs for transporting metal bars, tubes, rods or the like from the rolling or drawing machines, and therefore, must be capable of withstanding rough usage and must have the requisite strength to carry relatively heavy loads even when hot. The carrier at present in common use comprises a flat or rectangular strip of metal bent to substantially U-shape, and is the best construction hitherto devised, but it is very far from satisfactory because of its liability to bend and to break after repeated straightening. 75

The construction shown in Figs. 1 to 6 comprises a metal rod 10 bent into an elongated loop, the first shape being indicated by the dot and dash lines 11 in Fig. 3, the abutting ends 12 of the rod being preferably located at about the midlength of the loop and welded together, although it is not absolutely necessary that they be secured together and this joint may be located at other positions in the loop. The next operation in forming the carrier is to take a standard or other pipe 13 as shown in Fig. 4 of the desired length and flatten it to substantially the shape shown in Fig. 5. This flattened pipe is then slipped over the elongated loop formed by the rod 10 with the spaced side bars 14 thereof in substantially the position shown in Fig. 5 and with both ends of the loop indicated in dot and dash lines 11 projecting from the opposite ends of the enclosing casing 13 as shown in Fig. 3. 85

One or both of the opposite sides of this enclosing casing, preferably both sides, are then further compressed between the side bars 14 as indicated at 18 in Fig. 6. This 100

draws the casing tightly about the bars 14 making a rigid construction, and these compressed portions 18 extend sufficiently between the bars 14 to effectively and rigidly hold them in the proper spaced relation. 5 The projecting end portions are then heated and compressed somewhat longitudinally so as to spread the loop somewhat as shown in dotted lines 15 of Fig. 3 at their free ends. These looped ends are then bent upwardly to a position indicated at 16 in Fig. 1 forming upright looped ends to receive hooks 17 from a suitable crane or other carrying device.

It will be evident from this construction 15 that the base portion between the upright loop portions 16 is retained at the proper width so that the carrier will readily stand along on the floor at the rolling or drawing machines to permit easy loading, and also 20 the enclosing casing member and side bars 14 cooperate with each other to provide a central or base portion which is very strong and rigid and will carry heavy loads of bars, rods, tubes or the like, a portion of which is 25 indicated at 9, without bending or deforming even when hot.

Figs. 7 and 8 show a slightly different construction of the enclosing casing member for the central or base portion. In this form 30 instead of using a continuous pipe, a metal plate or strip is used. After the rod 10 has been bent into the elongated loop, the opposite end portions spread somewhat as indicated at 15 in Fig. 3 and then bent upwardly to the position 16 as shown in Fig. 1, the plate 35 19 is formed to substantially the shape shown in Fig. 7 and is then wrapped around the side bars 14 of the central or base portion as indicated in Fig. 8, and then, the abutting edges of the plate are welded as indicated at 40 20 in Fig. 8. This produces substantially the same structure as shown in Figs. 1 to 6. If preferred, the plate 19 may be wrapped around and placed in position on the side bars of the loop before the end portions are 45 widened or bent to the upright position.

It has been found that the above construction 50 provides a carrier which is much stronger and less likely to be deformed or bent out of shape under heavy loads than any other carrier construction heretofore devised, and particularly is this true when the carrier is heated, as it must be when passed through the annealing furnace with the rods, bars or 55 tubes to be annealed. It also provides a carrier sufficiently light in weight to be properly positioned by hand at the machines where they are to be loaded, and the base portions are of sufficient width so that they will 60 readily stand alone during the loading operation. They are also much stronger and much more rigid in proportion to the metal used than is the old type of carrier.

Having thus set forth the nature of my invention, what I claim is:

1. A metal carrier comprising a metal bar in the form of a loop with substantially parallel sides forming a base portion and upright end portions, and an enclosing member of sheet metal enclosing the said base portion. 70

2. A metal carrier comprising a metal bar in the form of a loop with spaced sides forming a base portion and upright end portions, and an enclosing member embracing the base portion and depressed somewhat between the 75 sides of the loop to retain them in spaced relation.

3. A metal carrier comprising a metal bar in the form of an elongated loop with the opposite end portions extending upwardly to 80 form upright looped ends and a central base portion connecting them, and an enclosing member embracing the two sides of the base portion.

4. A metal carrier comprising a metal bar 85 in the form of an elongated loop having spaced side members, the opposite end portions being extended upwardly to form upright looped ends and a central base portion connecting them, and an enclosing member 90 embracing the two sides of the base portion and depressed somewhat between them to retain them in spaced relation.

5. A metal carrier comprising a circular metal bar in the form of an elongated loop 95 with spaced side members, the opposite end portions of the loop being bent upwardly to form a substantially U-shaped member with bowed ends to receive lifting hooks, and a metal casing member enclosing said base portion for substantially the length thereof, said casing member being depressed on one side 100 to extend between the side members of the base portion and retain them in spaced relation.

In testimony whereof I affix my signature.
JAMES R. COE.
